UNITED STATES PATENT OFFICE.

WALTER H. WHITTIER, OF GRAND RAPIDS, MICHIGAN, ASSIGNOR TO GRAND RAPIDS REFRIGERATOR COMPANY, OF GRAND RAPIDS, MICHIGAN, A CORPORATION OF MICHIGAN.

REFRIGERATOR-FLUE CONSTRUCTION.

Application filed December 17, 1923. Serial No. 681,069.

This invention relates to a flue construction to be located between an upper ice chamber in a refrigerator and a provision holding compartment in the refrigerator directly below the ice chamber, said flue extending through the horizontal partition which separates the two compartments or chambers in the refrigerator from each other. It is a primary object and purpose of the invention to make a very simple and easily and economically constructed and assembled flue construction for interposition between and connection of the ice chamber and lower provision compartments of refrigerators whereby air circulation in the refrigerator may be had in connection with other flues between the ice chamber and a side provision compartment, and between the said lower provision compartment and the side provision compartment.

An understanding of the invention may be had from the following description, taken in connection with the accompanying drawing, in which,

Fig. 1 is a fragmentary transverse vertical section through a refrigerator equipped with the flue construction of my invention.

Fig. 2 is a plan view of an element of the construction prior to its being formed into a covering ring for the upper edge portions of lining flanges which surround the flue opening in the dividing partition between the ice chamber and lower provision compartment, and

Fig. 3 is an enlarged fragmentary vertical section through one side of the flue construction.

Like reference characters refer to like parts in the different figures of the drawing.

The refrigerator may be of any desired construction and include three compartments or chambers, an ice chamber located at one side and in the upper portion of the refrigerator, a lower provision chamber positioned directly below the ice chamber, and a side provision compartment or chamber having a height equal to the combined heights of the ice chamber and the lower provision chamber. The inner casing of the refrigerator has sides 1 with a vertical partition 2 dividing the space within the casing and a horizontal partition 3 between one side 1 and the vertical partition 2 to divide one of the side compartments made by the

vertical partition into an upper ice chamber 4, a lower provision chamber 5, while the side provision chamber 6 is located at the opposite side of the vertical partition 2, as indicated in Fig. 1.

Each compartment or chamber is lined with sheet metal or porcelain covered sheet metal, the lining to one side of the chamber 6 being indicated at 7. In the provision chambers, the linings are covered on their inner sides with porcelain which is baked theron, making a very clean and sanitary lining. The provision chamber 5 has a lining with sides 8, top 9 and a back and bottom, the top 9 at its central portion having an opening therethrough with the metal turned upwardly to make a continuous annular flange which passes through a like opening made in the partition 3, the flange extending a short distance above the upper side of the partition. The openings in the partition and top 9 of the lining are elongated with rounded ends and the longest dimension of the openings is from front to rear, preferably.

The ice chamber 4 is lined with sheet metal having sides 11 and a bottom 12, a back and top completing the lining. An opening is made in the bottom 12 similar in shape to the openings in the top 9 of the lower provision chamber lining and in the partition 3, an upturned flange 13 surrounding the opening and being located around the upper portions of the flange 10 heretofore described. The upper edges of the two flanges 10 and 13 lie substantially in the same horizontal plane.

A member 14 of sheet metal, shown in Fig. 2, having spaced apart parallel sides with connecting rounded ends is used and shaped into a form substantially U-shape in cross section, the outer leg 15 thereof being located around the flange 13 and bearing thereagainst, the inward and downward bend 16 lying over the upper edges of the flanges 10 and 13 and the inner leg extending downwardly inside of the flange 10. The leg 15 is secured to the flange 13 by solder, preferably, and the leg 17 extends downwardly inside of the flange 10 and may be spaced a short distance therefrom. After the parts are assembled, the lower edge portion of the inner leg 17 may be pressed and curved by any suitable tool so as to

bear against the inner sides of the flange 10, as indicated at 18.

This construction of flue is simple and practical. Of course in the complete refrigerator, flue openings are made through the vertical partition 2 adjacent its upper and lower edges, like those shown in my Patent No. 970,672, granted Sept. 20, 1910 in order to provide for a continuous circulation but this is not shown as the invention is directed to the flue construction through the horizontal partition dividing the ice and lower provision chambers. The appended claims define the invention which 15 is to be considered as comprehensive of all forms of structure coming within the scope of the said claims.

I claim:

1. In a refrigerator having an upper and 20 lower chamber, a metallic lining for the upper chamber having an opening in its bottom and the metal surrounding the opening being turned upward to form a flange, a lining for the lower chamber having an 25 opening in its top and the metal surrounding said opening being turned upward to form a flange which extends into the first named opening, and a continuous inverted channel member embracing and covering 30 the edges of the first and second named flanges.

2. In a refrigerator having an upper and

lower chamber, a metallic lining for the upper chamber having an opening in its bottom and the metal surrounding said 35 opening being turned upward to form a flange, a lining for the lower chamber having an opening in its top and the material surrounding said opening being turned upward to form a flange which enters the first 40 named opening, and a continuous inverted channel member embracing and covering the edges of both flanges and soldered to the outer flange, said inner flange being movable relative to the said channel member. 45

3. In a refrigerator having an upper and lower chamber, a metallic lining for the upper chamber having an opening in its bottom and the metal surrounding said opening being turned upward to form a flange, a lining for the lower chamber having an opening in its top and the material surrounding said opening being turned upward to form a flange which enters the first named 50 opening, and a continuous inverted channel member embracing and covering the edges of both flanges, said member being soldered to the outer flange and rolled tight to the inner flange after assembly, said inner flange being movable relative to said channel member. 55

In testimony whereof I affix my signature.

WALTER H. WHITTIER.
